UNITED STATES PATENT OFFICE.

JOHN T. OLIVE, OF WORDEN, ILLINOIS.

CHECK-HOLDER.

1,341,720.

Specification of Letters Patent. Patented June 1, 1920.

Application filed January 26, 1920. Serial No. 354,083.

To all whom it may concern:

Be it known that I, JOHN T. OLIVE, a citizen of the United States, residing at Worden, in the county of Madison and State of 5 Illinois, have invented a new and useful Check-Holder, of which the following is a specification.

This invention relates to improved check holders adapted for use in connection with 10 mine cars for holding and depositing a check identifying the load of coal or ore carried up from a mine to a tipple to be dumped, as usual, the device being designed to hold the check in position so as to permit 15 it to be readily inserted or removed and to obviate the possibility of the check being lost and the dispute arising as to the one who is entitled to the benefit of the load, as well as obviating parts which project and are likely 20 to hinder the coupling together or uncoupling of the cars or catching the clothing of the driver or injuring the latter.

A further object of the invention is to provide a check holder which is comparatively simple in construction and therefore 25 can be very economically produced from sheet metal and readily applied to the front portion of cars as in ordinary use in mines.

With the above and other objects in view 30 which will appear as the description proceeds, the invention resides in the combination and arrangement of parts and in the details of construction hereinafter described and claimed, it being understood that within 35 the scope of what is claimed, changes in the precise embodiment of the invention shown can be made without departing from the spirit of the invention.

In the accompanying drawings:

40 Figure 1 is a front elevation of my improved check holder with a check mounted therein;

Fig. 2 is a rear elevation;

Fig. 3 is a plan view;

45 Fig. 4 is a vertical sectional view taken on line 4—4 of Fig. 1, and

Fig. 5 is a rear elevation of a modified form of check holder.

In mines at the present time, it is the 50 usual custom to employ checks having numbers thereon to identify the particular miner who loads a car and who is entitled to credit for the same, when the car reaches

the tipple to be dumped. On nearly all cars in mines a big spike or nail is driven from 55 the inside of the car to the outside at the front and then bent into a hook in order to receive the check thereon. This however is rather dangerous as the man or boy who drives the mule which pulls the coal car has 60 no place to ride on except by standing on a short drag chain about three and a half feet long, termed a tail chain. The driver rides on this chain by placing his two feet on the chain and his back against the car 65 and since the only way of stopping the car is by jumping off the chain and to the ground and bracing his body against the front of the car, the spike or nail or check hook is always in the way and the driver is 70 apt to get pronged or injured in the back, in addition to the fact that the check is often caused to be displaced or slipped off, causing dispute as to whom the car belongs, and as to who is entitled to credit for the 75 load. At the front of the car is a door and it is convenient for the check puller to obtain access to and remove the check when the car is taken up into the tipple to be dumped, and it is desirable to mount the 80 holder on the front of the car but in order to obviate the objections to the spike nail or check hook above specified, I have devised the present invention.

As shown in the drawings in which like 85 reference characters designate corresponding parts throughout the several views, the improved check holder is preferably made of sheet metal or other construction having suitable stiffness and spring metal qualities 90 so as to provide a front portion 10, the sides of which are formed with inwardly extended portions 11 and outwardly extending flanges 12 suitably apertured as indicated at 13, for receiving fastening screws or the like by 95 which the device is secured on the front of the car at the door thereof. The front portion 10 is provided with a cut-out or recess 14 extending from its upper edge and medially of the front portion toward the 100 bottom thereof, so as to render visible the check 15 mounted therein. It is to be understood that these checks are provided with various numbers and an opening 16 ordinarily employed for holding the check on 105 the spike nail or check hook, commonly em-

ployed. The checks may be left without this opening or as so provided, may be drawn with facility. The number of the check is partly exposed through the opening or recess 14 and the bottom edge portion of the blank from which the check holder is made, preferably of galvanized sheet metal or the like, is provided with an extension curved or bent rearwardly and upwardly as indicated to form a spring tongue or prong 17 which is tapered toward its upper end, said upper end being forwardly disposed to normally project through the opening or recess 14 when the check is removed, and projecting above the top edge of holder at the front portion thereof and curved rearwardly to form a finger piece 18, facilitating the release of the check. This tongue or prong being pressed forwardly resiliently, tends to hold the check in position by frictionally holding the same against the rear faces of the front wall of the holder.

In the form of the invention shown in Fig. 5 of the drawings, the construction is the same, except in lieu of the spring tongue or prong 17, which is bent from the intermediate portion of the blank and the front portion thereof rearwardly and upwardly curved toward the same and in spaced relation to the lower portion of said front portion of the holder, said lower edge is provided with rearwardly and upwardly bent strips 19, forming a prong or tongue at either side of the recess in the front portion of the holder and projecting over the recess at the sides of the latter as shown. Each of the prongs or tongues in the form shown in Figs. 1 to 4 inclusive as well as shown in Fig. 5, are curved or bent outwardly after being turned rearwardly and upwardly and then curved forwardly toward the top portion or edge of the holder, the upper extremities extending above the edge of the front portion and turned rearwardly to facilitate application of the check guided from the same into the holder and between the prong and front portion, as shown and described. Thus, it will be seen that the front portion of the check is relatively stiff, and serves to protect the gripping portion or prong as well as to prevent displacement of the check from within the same. The device is relatively flat, and is made of relatively stiff material. With the proper spring action the check will be efficiently held in position and will not become displaced by reason of the driver or checker placing his back against the front of car in juxtaposition to or over the holder. Furthermore, the possibility of injury to the driver is prevented, as compared with the spike nail or check hook as at present in use. As each loader has a particular number for his checks, it is important that the checks should not become lost or displaced, in or-

der to avoid disputes and with the present invention, the identification as to whom the credit for the coal is to be given, is insured. The device does not project sufficiently to interfere with the coupling or uncoupling of the cars, and therefore is not likely to catch in one's clothing or in projecting objects or injury or damage, or possible displacement of the checks. Each holder is made of a single piece of sheet metal or the like, thereby permitting it to be very economically produced and readily applied.

I am aware of the Patent Number 1,101,426, but claim an improvement in the construction of the present device thereover, in view of the fact that, as a single body employed, an automatic lock is obviated. Also, since it is only possible to stop a car when in motion, and also when the car has been landed on the shaft bottom, by placing one's back against the front of the car, unlocking of the device shown in this patent would result. Furthermore, since that is the only method that can be employed by the driver in the mine to stop the car, including the stopping thereof when landed on the shaft bottom so as to be put on the cage or elevator one at a time and hoisted to the top where they are weighed and dumped, the attendant will be also protected from injury in pushing the car onto the cage or elevator unless the car runs very free and since the device is relatively flat and obviates the necessity of providing a nail or hook as heretofore done, injury to the driver, checker or attendant at the elevator will be obviated. It is also possible to employ sufficiently large numbers to accommodate three figures so as to permit the same to be readily seen in and out of the mine.

Having thus described my invention what I claim is:

1. A holder for mine car checks comprising a blank section of sheet metal bent at right angles at the sides thereof to form a relatively shallow casing having oppositely extending flanges for mounting the device on front of the car, the front portion being provided with a recess communicating with its upper edge and the bottom portion being formed with an integral extension bent rearwardly and upwardly to form a gripping tongue coöperating with the front portion to hold a check therein.

2. A check holder of the class described comprising a section of spring metal in the form of a blank having a front portion formed with a recess medially of its ends, the front portion being bent rearwardly at right angles to form sides, said sides being relatively shallow and having outwardly extending apertured flanges, the bottom edge of the front portion being formed immediately with a tapered tongue curved rearwardly and upwardly, the upper portion of

the tongue being curved forwardly below the top edge of the front portion and then rearwardly and tending to spring normally toward said front portion to retain a check 5 therein, the bottom portion of the tongue serving to prevent displacement of the check.

In testimony that I claim the foregoing as my own, I have hereto affixed my signature in the presence of two witnesses.

JOHN T. OLIVE.
